(57) **CLAIM**

The ornamental design for a globe light fixture, as shown and described.

DESCRIPTION

FIG. 1 is a front elevational view of the globe light fixture in accordance with the present invention;

FIG. 2 is a top plan view thereof;

FIG. 3 is a bottom plan view thereof;

FIG. 4 is a bottom perspective view thereof; and,

FIG. 5 is an enlarged fragmentary view thereof, showing only the finial portion of the light fixture, with the remaining structure being omitted for illustrative purposes only.

1 Claim, 4 Drawing Sheets
